UNITED STATES PATENT OFFICE.

EDWARD KRANCHER, OF BROOKLYN, NEW YORK.

HAT-PIN RETAINER.

SPECIFICATION forming part of Letters Patent No. 703,795, dated July 1, 1902.

Application filed October 16, 1901. Serial No. 78,831. (No model.)

To all whom it may concern:

Be it known that I, EDWARD KRANCHER, a citizen of the United States, and a resident of the city of New York, borough of Brooklyn, in 5 the county of Kings and State of New York, have invented a new and Improved Device for Protecting Hats, of which the following is a full, clear, and exact description.

My invention relates to means for protecting ladies' hats and auxiliary parts, such as 10 ribbons and ornaments, from the effects of mutilations caused by the use of hat-pins.

The invention consists in the novel construction and combination of the several 15 parts, as will be hereinafter fully set forth, and pointed out in the claim.

Reference is to be had to the accompanying drawings, forming a part of this specification, in which similar characters of reference indicate corresponding parts in all the figures.

Figure 1 is a perspective view of a hat upon which my device is employed in connection with an ornament. Fig. 2 is a fragmentary sectional view of the same. Fig. 3 is an enlarged sectional view of certain details, and Fig. 4 is a sectional view showing the device applied to the plain portion of a hat.

The body 1 of the hat may be provided with ribbons 2 and ornaments 3 of various 30 kinds in the usual manner, as shown in Figs. 1 and 2, or may be plain, as in Fig. 4.

A button is made of two portions 4 and 14, the portion 4 being cupped at 5 for the purpose of affording a grip against the substance 35 of the hat. Upon the member 4 is mounted a screw-threaded cylindrical portion 7 integral therewith, this cylindrical portion being open-ended, as shown more particularly in Fig. 3, and provided with constricted rings 6 8. In 40 this cylindrical portion is mounted a filling 13, of cork, fiber, or any similar substance, the same being held in place by the combined effect of the screw-threads 7, surrounding it, and the constricted rings 6 and 8. The filling, being compressible, can be pushed out of 45 the cylindrical space when desired for the purpose of substituting a new filling or for any other purpose. The constricted rings 6 and 8 prevent the filling from projecting out- 50 wardly from the hollow metallic member. The

other member 14 is provided with screw-threads 9 and also with a horn-shaped end 10. This member is adapted to screw upon the threads 7, so that the two members of the button can be secured together. The cupped 55 edges 15 and 5 engage the respective inner and outer surfaces of the hat, thus preventing the button from becoming detached and preventing the members from moving relatively toward each other.

Where ornaments 3 are used, they are placed directly against the body of the hat and the members of the button pass through them, as shown in Figs. 1 and 2.

My invention is used as follows: The two 65 members of the button being placed in position, as indicated in Figs. 1 and 2 and in Fig. 4, the shaft 11 of the hat-pin is simply stuck through the filling 13 instead of through the hat direct. This of course saves the mutilation 70 of the body of the hat and of various ribbons and ornaments usually damaged by the use of the hat-pin and enables the hat-pin to be placed precisely in the same position every time. Of course any number of 75 these buttons may be placed upon a hat, and the hat-pin can be run through them upon either side of the hat.

Where ornaments are used, the ornaments are mounted upon the buttons in the manner shown, and as the larger horn-shaped end 10 of the button is made tolerably small and the head 12 of the hat-pin may be chosen tolerably large the hat-pin will have the appearance of being stuck directly through the 85 ornament, but without the possibility of mutilating the same.

My purpose in making the open ends horn-shaped is to enable the point of the hat-pin to find its way into the filling. The constricted ring 6 answers virtually the same purpose and to all intents and purposes renders the button horn-shaped inside the hat. This is for the purpose of enabling the point 90 of the hat-pin after passing through the hair to find its way out of the hat by passing through the filling. In this connection it should be noted that ladies are usually quite proficient in inserting a hat-pin at the particular place every time, and that they 100

have no trouble in inserting the pin through the filling of my device upon either or both sides of the hat.

Having thus described my invention, I claim as new and desire to secure by Letters Patent—

As an article of manufacture, a hat-protecting device comprising a composite button made of open-ended members provided with screw-threads and detachably secured together, and a resilient filling mounted in one

of said members, and detachably secured independently of the other member, for the purpose of receiving the shaft of a hat-pin.

In testimony whereof I have signed my name to this specification in the presence of two subscribing witnesses.

EDWARD KRANCHER.
